RETREAD PAVER

William A. Cost and Joseph W. Hartley, Indianapolis, Ind., assignors, by mesne assignments, to The Jaeger Machine Company, Columbus, Ohio, a corporation of Ohio

Application November 9, 1934, Serial No. 752,229

24 Claims. (Cl. 94—40)

Our invention relates to re-tread pavers, or machines adapted to be propelled over a road and, while so moving, to engage loose aggregate on the road surface, to mix such aggregate with a suitable binder, and to discharge and distribute the mixture in the desired cross-section.

It is the object of our invention to produce a machine of this type which will have advantages over prior machines. More specifically, it is our object to produce a machine which will be self-propelled and which will be supported upon four ground-engaging wheels all of which are driven and all of which may be steered, the rear wheels being steerable independently of the front wheels for a purpose which will hereinafter become apparent. A further object of our invention is to elevate the un-treated aggregate from the road surface and to subject it to a thorough mixing with the binder by a mechanical mixer. Still another object of our invention is to produce a re-tread paver which, although operated on a relatively uneven sub-grade surface, will distribute the paving material smoothly and evenly.

In carrying out our invention we construct the vehicle with a main frame supporting an engine which supplies power for moving the vehicle and for driving the mixing device as well as for effecting certain adjustments. The main frame of the vehicle is supported upon front and rear driving wheels, one pair of such wheels preferably being mounted upon a truck pivotally connected to the main frame on a longitudinal axis so as to afford a three-point suspension for the main frame. Both the front wheels and the rear wheels are arranged to be driven from the engine and also to be steerable.

Beneath the main frame of the vehicle we suspend a sub-frame carrying a mechanical mixing device preferably in the form of a pug-mill mixer driven from the vehicle engine. In advance of the pug-mill, the sub-frame carries a pair of forwardly and outwardly diverging ground-engaging blades adapted to gather aggregate and to direct it to the pug-mill as the machine moves along the road. The main frame carries one or more tanks containing a supply of liquid binder which is discharged on to the aggregate as it enters the pug-mill and is thoroughly mixed with the aggregate as it passes rearwardly through the pug-mill.

Loosely suspended from the sub-frame which carries the pug-mill are a pair of relatively long ground-engaging shoes upon which, at the rear of the machine, is mounted a distributing blade adapted to distribute to any desired cross-section

the mixture discharged from the rear end of the pug-mill. Means controlled from an operator's station on the main frame are provided for adjusting the distributing blade in a vertical plane relative to the shoes which carry it.

The accompanying drawings illustrate our invention: Figs. 1 and 2 are a plan and a side elevation respectively of the complete machine; Fig. 3 is a view similar to Fig. 2 but with parts of the machine broken away to illustrate the construction more clearly; Fig. 4 is a plan view of the sub-frame, pug-mill, gathering blades, and distributing blade; Fig. 5 is a detailed view illustrating in elevation, as indicated by the line 5—5 of Fig. 4, the mechanism by which the distributing blade is vertically adjusted relatively to the shoes which support it; and Figs. 6 and 7 are partial transverse vertical sections on the lines 6—6 and 7—7 respectively of Fig. 1.

The main frame of the machine shown in the drawings comprises longitudinal side members 10, a front cross member 11, a rear cross member 12, and intermediate cross members 13 and 14, the cross member 13 being located near the front end of the machine and the cross member 14 near the rear end. The cross member 13, which is preferably tubular in cross-section, carries steerable front supporting wheels 20 near its ends, such wheels serving to support the front end of the machine. The rear end of the machine is supported upon a truck comprising a transverse tubular member 21 carrying the rear wheels 22 and pivotally attached to the main frame through the medium of a longitudinally extending pivot shaft 23 extending between the cross members 12 and 14 of the main frame, the member 21 being provided with a rigid bearing 24 of considerable longitudinal extent for the shaft 23.

As previously set forth the rear wheels as well as the front wheels of the machine are steerable. To this end, each of the rear wheels 22 is mounted upon a stub axle projecting outwardly from a hollow casing 30, the upper end of which is rigid with a vertical spindle 31 mounted in a suitable bearing 32 on the member 21. The two rear wheels are interconnected for joint steering movement by means of arms 33 which are secured respectively to the spindles 31 and which are interconnected by the usual tie rod 34, all as shown in Figs. 1 and 7.

The mounting of the front wheels is generally similar to that of the rear wheels, each front wheel being mounted at one side of a hollow casing 35 rigid with a vertical spindle 36 carried

in a suitable bearing 37 at one end of the tubular cross member 13. Rigid with the spindles 38 are arms 39 which are interconnected by means of a tie rod 39'.

5   Mounted upon the main frame of the machine, preferably near the front end thereof, is a power plant 40, preferably an internal-combustion engine, which supplies power for driving the front and rear wheels. The drive from the engine 10 to the wheels is through a friction clutch 41, controlled by a clutch-operating lever 42 and also through a change-speed transmission mechanism 43. Details of the change-speed transmission mechanism are not illustrated, as any desired device of this kind may be used to provide the desired speed ratios.

15   The change-speed transmission mechanism is operatively connected to the driven element of the clutch 41 as by the shaft 44 and includes 20 two driven shafts 45 and 46 (Figs. 1 and 3) connected respectively to the front and rear wheels.

25   As is evident from Fig. 7, the drive for the rear wheels includes differential mechanism enclosed within a housing 50 centrally located on the member 21, such differential mechanism including a forwardly extending driving shaft 51 and two laterally extending driven shafts 52. In approximate alignment with the two shafts 52, the casings 30, which respectively carry the two rear 30 wheels, are provided with shafts 53 connected respectively to the shafts 52 through intermediate shafts 54. To permit steering movement of each of the wheels 22, each shaft 54 is extensible and is connected to its associated shafts 52 and 35 53 through universal joints 55.

35   Each of the shafts 53 is operatively connected to its associated wheel 22 by means of power-transmission mechanism located within the casing 30. To this end, we may provide within the 40 casing 30 a gear 56 rotatable with the wheel 22, an idler 57 meshing with the gear 56, and a pinion 58 meshing with the idler 57, the pinion 58 being rotatable with the shaft 53.

45   The drive shaft 51 of the differential mechanism enclosed in the casing 50 is operatively connected to the driven shaft 46 of the change-speed transmission mechanism by means of a propeller shaft 60 connected to the shafts 46 and 50 through universal joints 61. The shaft 46 50 may have associated with it suitable brake mechanism 62 for the vehicle.

55   The drive train for the front wheels is substantially the same as that just described for the rear wheels, the front-wheel driving shaft 45 being connected through a propeller shaft 64 with differential mechanism located in the casing 65 68 (see Fig. 3), such differential mechanism being operatively connected to the front wheels 20 through flexible transversely extending shafts 60 and gearing located within the casing 35.

65   Beneath the main frame of the vehicle there is suspended a sub-frame 68 carrying a pug-mill mixer 69 including a pair of longitudinally extending shafts 70 upon which inclined mixing 70 blades 71 are mounted, as is customary in pug-mills. For the purpose of driving the pug-mill, we provide an engine-driven shaft 73 conveniently mounted in and projecting rearwardly from the casing of the change-speed transmission mechanism 43, as shown in Fig. 1. Suitable clutch mechanism controlled by a control member 74 is employed for connecting the pug-mill to the power plant 40 at will. The drive for the pug-mill is through an extensible shaft 75 connected through universal joints to the shaft 73

and to a shaft 76 which is rotatably mounted in a casing 77 containing gearing or other mechanism by means of which the shaft 76 is connected to the two longitudinally extending shafts 70 of the pug-mill, as shown in Figs. 3 and 6.

5   The pug-mill 69 is open at its front and rear ends, laterally spaced vertical plates 80 and an inclined apron 81 located at the front end of the pug-mill serving to direct aggregate into the mill as the machine moves forwardly along the road. Extending forwardly and outwardly from the front ends of the two plates 80 are gathering blades 82 adapted to engage aggregate on the road surface and to move it inwardly to a point where it can pass rearwardly between the two plates 80.

10   The sub-frame 68 and the parts mounted upon it, such as the pug-mill 69, the plates 80, apron 81, and gathering blades 82, are all vertically adjustable as a unit relative to the frame of the machine. To this end, the sub-frame 68 is suspended from the main frame of the machine by a front pair of suspension chains 85 and a rear pair of suspension chains 86. The rear chains 86 extend upwardly from their point of attachment to the sub-frame 68 and around transverse 20 rotatable shafts 87 mounted on the main frame of the machine and conveniently supported from the intermediate cross member 14. (See Fig. 6.) The front pair of chains 85 extend over sheave pulleys 88, located above their points of attachment to the sub-frame 68, and thence rearwardly to the shafts 87, to which they are secured. The two shafts 87 are adapted to be rotated by irreversible power-transmission mechanism, such as worm gearing, contained in casings 89.

25   For the purpose of holding the sub-frame 68 in a central position laterally of the machine we employ hinge members 90 and 91 pivotally connected to the sub-frame at the front and rear thereof on transverse axes. The front hinge 40 member 90 extends forwardly from its point of pivotal connection to the sub-frame 68 and is pivotally connected on a transverse axis to the front cross member 11 of the main frame. The front hinge member 90, in addition to locating 45 the sub-frame 68 laterally, also transmits draft to it. The rear hinge member 91 extends upwardly and rearwardly from its point of attachment to the sub-frame 68 and is pivotally connected at its rear end to a member 92 which is 50 longitudinally slidable in a suitable guide 93 carried by the rear cross member 12 of the main frame.

55   The binder which is to be mixed with the aggregate in the pug-mill 69 may be carried in a 55 pair of tanks 95 mounted at the sides of the main frame of the machine. Binder from the tanks 95 is sprayed upon aggregate entering the pug-mill 69 through a discharge nozzle 96 located adjacent the front end of the pug-mill. We 60 prefer to control the rate at which binder is discharged from the nozzle by the mechanism set forth in the Patent No. 2,064,365 which mechanism includes a valve 97 for controlling the rate of binder-discharge from the nozzle 96, a swinging vane 98 mounted between the plates 80 and adapted to rest upon the surface of aggregate passing between such plates, and an operative connection 99 between the valve 97 and vane 98, whereby the amount of binder supplied to the 70 pug-mill is accurately proportioned to the amount of aggregate entering the pug-mill. The Wallace application above referred to contemplates that the binder emerging from the nozzle 96 will be subjected to a constant discharge head 75

which is obtained by connecting the nozzle 96, through the valve 97, to the discharge of an engine-driven pump 100 which withdraws binder from the bottom of either of the tanks 95 through pipes 101 and returns such binder to the tanks through overhead discharge pipes 102. Each of the pipes 101 is provided with a valved fitting 103, adapted for connection to an outside source of binder-supply, and also with valves 101', while the discharge pipes 102 are provided with valves 102'. By suitable adjustment of the valves, the pump 100 can be used to draw binder from a source of supply located at either side of the machine and to discharge it into either or both of the tanks 95. When the machine is in operation, the valves can be manipulated so that the pump will draw binder from either supply tank and discharge the excess into either tank.

The aggregate and binder entering the pug-mill 69 are thoroughly mixed together during their rearward passage through the pug-mill and are discharged upon the sub-grade surface through the open rear end of the pug-mill. To distribute this material to the desired cross-section, we prefer to employ a transversely extending distributor blade 105 which is supported at the rear of the machine from two longitudinally extending ground-engaging shoes 106. These shoes are drawn over the sub-grade surface with the machine by means of links 107 which connect their front ends with downwardly extending arms 108 on the sub-frame 68. (See Figs. 2 and 4.)

The distributing blade 105 is not mounted rigidly upon the rear ends of the shoes 106 but instead is supported therefrom through the medium of adjustable mechanism by means of which its vertical disposition may be varied to control the cross-section in which the paving material discharged from the pug-mill 69 is distributed. This adjustable mechanism includes a pair of generally parallel links 110 and 111 located on each side of the machine. The front ends of each pair of these links are pivotally connected on vertically spaced axes to a bracket 112 extending upwardly from the associated shoe 106 in advance of the rear end thereof, while their rear ends are connected to a vertically extending member 113 secured to the rear face of the distributing blade 105. The lower link 110 of each pair of links is arched, as is clear from Figs. 2 and 3, to pass over the top of the distributing blade 105 and over a blade re-enforcing angle 114.

The two ends of the distributing blade 105 are independently adjustable in a vertical plane by swinging arms 115 which are pivotally mounted on transverse axes on the respective shoes 106 and the free ends of which are connected by links 116 to the associated links 110. Conveniently, each of the arms 115 is rigid with the driven shaft 60 of irreversible power-transmission mechanism, such as worm gearing, contained in a casing 117 mounted on the associated shoe 106. If desired, a stationary graduated scale 118 may be associated with each of the arms 115 to indicate the adjusted position thereof, and thereby to indicate the height of each end of the distributing blade 105 above the sub-grade surface upon which the shoes 106 rest.

The assembly of shoes 106, distributing blade 105, and the mechanism interconnecting them is prevented from swinging laterally over the road surface by means of a stabilizing link 120 (Fig. 4) which extends generally transversely of the machine and has its ends pivotally secured to the sub-frame 68 and the blade angle 114.

The blade 105 is preferably not straight in plan but instead is of V-shape with its apex located near the longitudinal center line of the machine, as is clear from Fig. 4, and with its two legs extending outwardly and rearwardly. These oblique legs serve to direct the paving composition toward the ends of the distributing blade 105 and tend to prevent it from accumulating to too great a depth near the center of the blade.

It may be desirable at times to distribute the paving material selectively between opposite ends of the blade 105, as when laying it in a sheet which is thicker at one side than at the other. To effect such selective distribution, we provide a swinging gate 122 rigid with a vertical shaft 123 disposed at the apex of the distributing blade, the angular position of the gate 122 being controlled by irreversible power-transmission mechanism, such as worm gearing, disposed within a housing 124 supported from the distributing blade.

The V-shape of the distributor blade 105 permits the paving material to be distributed in a sheet having either a plane or a crowned upper surface, the slope of surface being varied as desired by adjusting the distributor blade about an axis disposed transversely of the machine. To this end, one link, here shown as the link 111, of each pair of generally parallel links supporting the distributor blade is made adjustable in length as by including it in a turnbuckle 130. By adjustment of these turnbuckles, the apex of the blade can be raised or lowered relatively to the ends of the blade to vary the amount of crown in the cross-section to which the paving material is distributed.

The adjustment of the swinging arms 115, which control the vertical disposition of the distributing blade 105, and the adjustment of the swinging gate 122 are preferably effected from an operator's station at the rear of the machine. We may therefore provide on the rear end of the main frame an operator's seat 135 adjacent to which are a pair of hand wheels 136 and 137, which respectively control the two swinging arms 115, and a third hand wheel 138 which controls the position of the swinging gate 122. Preferably, the two hand wheels 136 and 137 are disposed in opposed relation on a common axis extending transversely of the machine and are respectively connected through suitable shafts and gearing with the driving shafts of the worm gearing contained in the housings 117. The hand wheel 138 is operatively connected to the driving shaft of the worm gearing located in the housing 124.

It may be desirable at times, and especially in cold weather to heat the binder contained in the tanks 95. For this purpose, each of such tanks is shown as provided with a U-shaped flue 140 which extends longitudinally of the tank for substantially the whole length thereof and which has inlet and discharge openings located exteriorly of the tank at the front end thereof. The inlet opening of each flue 140 is disposed in line with a burner 141 mounted on the main frame in position to discharge hot gases into the flue. The burner 141 is supplied with fuel from a fuel-tank 142 and with air under pressure from a compressor 143.

As a practicable machine embodying our invention is of large dimensions and considerable weight, relatively great effort is required to effect some of the adjustments. The most notable of such adjustments are the steering of the front and rear wheels and the raising and lowering of the sub-frame 68 and the parts it carries. These

adjustments we prefer to effect by means of power derived from the engine under manual control.

As previously indicated, the shafts 87 are preferably adjusted through irreversible power-transmission mechanisms located in the casings 88; and similar irreversible power-transmission mechanisms are preferably provided to effect steering adjustment of the front and rear wheels. 10 As shown in the drawings, worm gearing contained in a casing 125 mounted on the front cross member 13 is employed to control the position of a horizontally swinging arm 126 connected by a drag link 126' with the arm 38 on one of the front steering spindles. A similar arrangement is employed at the rear end of the machine, where worm gearing mounted in a casing 127 controls the position of the horizontally swinging arm 128 which is connected by a drag link 128' with the arm 38 on one of the rear steering spindles.

For the purpose of effecting the indicated power adjustments, we have shown the gearing by which steering of the front wheels is effected, the gearing by means of which steering of the rear wheels is effected, and the two sets of gearing which respectively control the two shafts 87 by means of which the sub-frame 68 is adjusted as connected respectively to rotatable driven elements 145 mounted in a control box 146. (See Figs. 1 and 3.) The control box also includes a rotatable driving element operatively connected through suitable power take-off mechanism and a shaft 147 with the engine 40. The connection of each of the driven elements 145 to the driving element is effected by a clutch controlled by a control lever 148. In addition to the four adjusting mechanisms mentioned above, the compressor 143 may also be driven through the control box 146.

40 In operation, the machine shown requires two operators, one located at the rear of the machine on the seat 135, as previously indicated, and the other stationed on a platform (not shown) between the two tanks 95. The latter operator, by manipulating control levers 150 of the change-speed transmission mechanism 43 controls the speed of the vehicle. In addition he can, by manipulation of the levers 148 of the control box 146, steer the front wheels 20, raise or lower either side of the sub-frame 68 and the parts it carries, and control the operative connection between the engine 40 and the compressor 143. The rear-wheel steering is conveniently under the control of the operator at the rear of the machine. For this purpose, there may be mounted near the operator's station at the rear of the machine a steering lever 151 operatively connected through suitable mechanism 151' (see Fig. 1) with that control lever 148 of the gear box 146 which controls the connection of the irreversible power-transmission mechanism which effects steering movement of the rear wheels.

As the machine passes along the road, the gathering blades 82 gather loose aggregate on the surface of the sub-grade and move it inwardly so that it may pass between the vertical plates 86 into the pug-mill mixer 69, the aggregate being lifted into the mixer by the apron 81. Preferably, the shafts 70 of the pug-mill extend forwardly over the apron 81 and have inclined blades 71 located above such apron, so that such blades will assist in moving the aggregate up the apron.

As it enters the pug-mill, the aggregate receives a supply of binder discharged from the nozzle 96, the amount of binder being propor-

tioned to the aggregate by the means described in the aforesaid application of Floyd D. Wallace. The blades 71 of the pug-mill are inclined to cause the aggregate and binder to be moved rearwardly through the pug-mill as the shafts 70 rotate, the blades serving additionally to effect a thorough mixing of the aggregate and binder.

The thoroughly mixed paving composition is discharged from the rear end of the pug-mill in advance of the distributing blade 105 and is distributed between the opposite ends of such blades by the swinging gate 122 under the control of the operator at the rear of the machine. This operator also controls the vertical disposition of the distributing blade so as to distribute the paving composition in the desired cross-section.

By making the front and rear wheels independently steerable, it is possible for the operator at the front of the machine to direct it in a course such that the gathering blades 82 will be most effective in gathering loose aggregate while the operator at the rear of the machine can steer the rear wheels to control the lateral disposition of the sheet of paving material laid by the distributing blade 105. Broadly, the independent steering of front and rear wheels in a re-tread paver is the invention of William A. Cost alone, and is covered in a co-pending application filed by him on November 9, 1934, and bearing Serial No. 752,230.

When the machine is to be transported over the road without mixing and laying a paving composition, the shafts 87 are rotated to raise the sub-frame 68 and lift the gathering blades 82, plates 86, shoes 106, and distributor blade 105 free of the road surface. The front ends of the shoes 106, when the sub-frame 68 is raised, are lifted by the draft-links 107, while their rear ends are lifted by chains 131 (Figs. 2 and 7) which extend between the sub-frame and shoes and which hang slack while the machine is operating to lay paving material.

We claim as our invention:

1. A re-tread paver for roads, comprising a wheel-supported frame, a pug-mill mixer carried by said frame, said mixer including a substantially horizontal longitudinal trough open at its forward end and one or more longitudinally extending rotatable shafts having helically inclined blades for moving material in said trough rearwardly, each of said blades having a radial length approximating the distance between its associated shaft and the bottom of said trough, and an apron sloping forwardly and downwardly at the forward end of said trough in position to engage aggregate on the road surface and elevate it into said trough as the paver moves along a road, at least one of said blades being disposed over said apron in position to engage aggregate thereon.

2. A re-tread paver for roads, comprising a frame; a pair of front supporting wheels and a pair of rear supporting wheels for said frame; both said pairs of wheels being independently steerable; an engine mounted on said frame; a driving connection from said engine to said front and rear wheels; means carried by said frame for elevating aggregate from the road surface near the front end of the frame, mixing such aggregate with a binder, and discharging the mixture upon the road surface near the rear end of said frame; and a distributor blade located in rear of the point at which such mixture is discharged.

3. A re-tread paver for roads, comprising a frame; a pair of front supporting wheels and a pair of rear supporting wheels for said frame; at

least one pair of said wheels being steerable; an engine mounted on said frame; a driving connection from said engine to said front and rear wheels; means carried by said frame for elevating aggregate from the road surface, mixing it with a binder, and discharging the mixture upon the road surface; and a distributor blade located in rear of the point at which such mixture is discharged.

10. A re-tread paver for roads, comprising a frame; a pair of front supporting wheels and a pair of rear supporting wheels for said frame; both said pairs of wheels being independently steerable; an engine mounted on said frame; a driving connection from said engine to at least one pair of said wheels; means carried by said frame for elevating aggregate from the road surface near the front end of the frame, mixing such aggregate with a binder, and discharging the mixture upon the road surface near the rear end of the frame; and a distributor blade located in rear of the point at which such mixture is discharged.

11. In a re-tread paver, a wheel-supported frame, a mixer carried by said frame, a trough-like body extending longitudinally of said frame, said mixer body being open at its front end to receive material on the road surface and open at its rear end to discharge mixed materials, and means for independently adjusting the front and rear ends of the mixer body relative to said frame.

12. In a re-tread paver, a wheel-supported frame, a mixer carried thereby, an apron positioned to elevate aggregate from the road surface and to discharge it into said mixer, and means for independently adjusting opposite sides of said apron to vary the angular position thereof about an axis longitudinally to the vehicle.

13. In a re-tread paver, a wheel-supported frame, a mixer carried thereby, an apron positioned to elevate aggregate from the road surface and to discharge it into said mixer, a pair of gathering blades rigid with said apron and diverging forwardly therefrom, and means for independently adjusting opposite sides of the unit consisting of said apron and gathering blades.

14. In a re-tread paver, a distributor blade for distributing a paving composition, said blade being of general V-shape in plan with rearwardly diverging legs, two blade-mounting members spaced laterally of the paver, a pair of substantially parallel links interconnecting each of said members with said blade, one link of each pair being adjustable in length, and means for vertically adjusting said blade.

15. In a re-tread paver, a frame, wheels supporting said frame, an engine, a driving connection between said engine and at least some of said wheels, a mixer supported from said frame in position to receive aggregate on the road surface as the paver is driven therealong, and means driven by said engine for adjusting said mixer relatively to said frame.

16. The invention set forth in claim 15 with the addition that said mixer includes a rotatable mixing element, and power-transmitting means including a flexible driving connection operatively interconnecting said rotatable element and said engine.

17. In a re-tread paver, a frame, wheels supporting said frame, an engine mounted on said frame, a driving connection between said engine and at least some of said wheels, a mixer supported from said frame in position to receive aggregate on the road surface as the paver is driven therealong, means for adjusting said mixer relatively to said frame, said mixer having a rotatable mixing element, and power transmitting means including a flexible driving connection

least one pair of said wheels being steerable; an engine mounted on said frame; a driving connection from said engine to said front and rear wheels; means carried by said frame for elevating aggregate from the road surface, mixing it with a binder, and discharging the mixture upon the road surface; and a distributor blade located in rear of the point at which such mixture is discharged.

4. A re-tread paver for roads, comprising a frame; a pair of front supporting wheels and a pair of rear supporting wheels for said frame; both said pairs of wheels being independently steerable; an engine mounted on said frame; a driving connection from said engine to at least one pair of said wheels; means carried by said frame for elevating aggregate from the road surface near the front end of the frame, mixing such aggregate with a binder, and discharging the mixture upon the road surface near the rear end of the frame; and a distributor blade located in rear of the point at which such mixture is discharged.

5. A re-tread paver for roads, comprising a wheel-supported frame, a mixer carried by said frame and having a longitudinally extending trough open at both ends and means within said trough for mixing and moving rearwardly material therein, an apron secured to the front end of said trough, said apron sloping forwardly and downwardly in position to elevate into the trough of said mixer aggregate disposed on the road surface as the paver travels therealong, and means for vertically adjusting the front end of said trough.

6. A re-tread paver, comprising a wheel-supported frame, a mixer carried by said frame and having a longitudinally extending trough open at both ends and means within said trough for mixing and moving rearwardly material therein, means for gathering aggregate disposed on the road surface and elevating it into said trough, said means including a pair of forwardly diverging blades connected with said mixer-trough, and means for independently adjusting vertically each side of the unit comprising said mixer-trough and blades whereby the position of such unit about a longitudinal axis may be varied relative to the frame.

7. A re-tread paver, comprising a frame, two laterally spaced supporting wheels mounted on said frame near the front end thereof, a rear truck comprising a transversely extending axle member having wheels mounted near its opposite ends, means interconnecting said truck and frame for relative angular movement about an axis disposed longitudinally of said frame, means carried by said frame for intermixing aggregate and binder, and a distributor blade for distributing the mixture discharged from said mixing means.

8. In a re-tread paver for roads, a transversely disposed, vertically adjustable distributor blade generally V-shaped in horizontal plan with rearwardly diverging legs, a vertical vane pivotally supported from said blade and swingable about a vertical axis disposed near the apex of said blade, means for adjusting said vane about its axis, and means for discharging a paving composition upon the road surface in advance of said vane.

9. In a re-tread paver, a frame movable over the sub-grade surface to be paved, supporting wheels for said frame, a pair of laterally-spaced, ground-engaging shoes of considerable longitudinal extent loosely connected to said frame and free to move vertically relative thereto, a trans-

operatively interconnecting said rotatable element and said engine.

18. In a re-tread paver, a wheel-supported frame, a mixer positioned below said frame, said mixer being provided with an apron extending forwardly and downwardly in position to engage and elevate into said mixer aggregate disposed on the road surface, flexible tension elements supporting said mixer from said frame, and a generally horizontal draft element having its rear end connected to said mixer and its front end connected to said frame.

19. In a re-tread paver, a wheel-supported frame, a mixer positioned below said frame, said mixer being provided with an apron extending forwardly and downwardly in position to engage and elevate into said mixer aggregate disposed on the road surface, flexible tension elements supporting said mixer from said frame, and a draft element having its rear end connected to said mixer and its front end connected to said frame.

20. In a re-tread paver, a wheel-supported frame, a mixer positioned below said frame, said mixer being provided with an apron extending forwardly and downwardly in position to engage and elevate into said mixer aggregate disposed on the road surface, flexible tension elements supporting said mixer from said frame, and a rigid draft element having its rear end pivotally connected to said mixer on a horizontal transverse axis and its front end pivotally connected to said frame on two axes, one of which is a horizontal transverse axis and the other of which extends longitudinally of the frame.

21. In a re-tread paver, a wheel supported frame, a mixer, flexible tension elements supporting said mixer from said frame, and means

preventing lateral and longitudinal movement of the mixer relatively to the frame; said means comprising two rigid members pivotally connected to said mixer on horizontal axes at the front and rear thereof and extending oppositely therefrom, said rigid members being pivotally connected to said frame.

22. In a re-tread paver, a wheel supported frame, a mixer, flexible tension elements supporting said mixer from said frame, and means preventing lateral and longitudinal movement of the mixer relatively to the frame.

23. In a re-tread paver, a distributor blade for distributing a paving composition, said blade being of general V-shape in plan and having rearwardly diverging legs, means for bodily adjusting said blade vertically with a movement of translation, and mechanism in addition to said means for rocking said blade about a horizontal transverse axis to vary the relative height of the center and ends of the blade.

24. A re-tread paver for roads, comprising an elongated frame; a pair of front supporting wheels and a pair of rear supporting wheels for said frame, each of said pairs of wheels being steerable independently of the other pair; an engine mounted on said frame; power-transmission mechanism operatively interconnecting said engine with said front and rear wheels; means carried by said frame for engaging aggregate on the road surface at a point near the front end of the frame, mixing such aggregate with a binder, and discharging the mixture near the rear end of the frame; and a distributor blade located in rear of the point at which such mixture is discharged.
